[57] CLAIM

The ornamental design for a combined street name and advertising sign, as shown and described.

DESCRIPTION

FIG. 1 is a perspective view of a combined street name and advertising sign showing our new design;

FIG. 2 is a top plan view thereof; and
FIG. 3 is a sectional view, on an enlarged scale, taken generally along section line 3—3 of FIG. 1.

FIG. 1

FIG. 3
